BY E. W. Marshall

ATTORNEY

Patented May 31, 1927.

UNITED STATES PATENT OFFICE.

WILLIAM L. CONRAD, OF BOSTON, MASSACHUSETTS.

PROCESS FOR CONDITIONING TEXTILE MATERIALS.

Application filed May 25, 1923. Serial No. 641,326.

This invention relates to a method or process of conditioning or finishing textile material.

The terms "conditioning" and "finishing" as used in this art include several operations, such, for instance, as boiling, washing, subjecting to a sour bath and chemic bath, piling, and so forth.

The methods now in use for conditioning textile material consume much time, involve a large labor expense, and the resulting product is not uniform.

This invention has for its salient object to provide a continuous process for conditioning textile material whereby the time consumed and labor required will be reduced to a minimum and the resulting product will be uniform.

Another object of the invention is to provide a process of finishing cloth whereby the goods will travel continuously from the first keir to the white bins or drying apparatus without interruption or handling.

Further objects of the invention will appear from the following specification taken in connection with the drawings, which form a part of this application, and in which the process is illustrated diagrammatically.

The invention briefly described consists of a process involving the combination of a plurality of separate units and so combining these units that the material will move continuously from the time it enters the first unit until the time it leaves the last unit.

The essential elements involved in the process are the keir, suitable chemical solution such as a sour bath, pile or stack, chemic or other suitable bath and a pile or stack receiving the material from the chemic or other bath. In the embodiment of the invention illustrated, material is led successively through a keir, washing machine, treating bath, piling mechanism, washing machine, chemic or other bath, piling mechanism and washing machine. These various units are so constructed and arranged that the time required for the finishing process is reduced from a relatively long period of time, which is required under the processes

now in use, to a relatively short period of time and the labor saved, particularly in the sour and chemic piles, has amounted in actual practice in one plant to many thousand dollars a year. Further details of the invention will appear from the following description.

The material from the gray room, or, in other words, the unbleached material, is first led to a keir A and the construction of this keir is set forth in detail in Patent No. 60 1,074,568 to Gantt granted September 30, 1913. This apparatus is used for boiling the material and preferably contains a caustic solution. The apparatus is designed to carry on the process continuously, that is to 65 say to operate on fabric in the open width or rope form, which is continuously fed into the keir in which the liquid is circulated and continuously withdrawn therefrom and the apparatus is constructed in such a manner 70 as to accumulate enough of the fabric between the entering and leaving points to allow the fabric to be subjected to the action of the liquid for a sufficient length of time to accomplish the cleaning thereof. As described in the patent, the fabric is deposited in the keir in zigzag folds and streams of water are directed against the fabric through pipes 10 thoroughly scouring the fabric as it enters the keir, these streams being caused 75 to permeate the fabric before it sinks beneath the surface of the more inert liquid in the keir. The folds of fabric in the keir are supported in zigzag folds on a frame 11 and the web or rope is continuously added 80 to the top of the pile and is simultaneously withdrawn from the bottom of the pile around guide rolls 12 and 13 and passes between squeezing rolls or wringers 14.

If desired, a plurality of keirs may be 85 combined and the fabric may be led from one keir into another.

From the keir A or from the last keir of a set, if a plurality is used, the fabric is led through the wringers or squeeze rolls 14 and 95 into a washing machine B of any suitable construction wherein the fabric is washed. From the machine B, the fabric passes through wringers or rolls 15 and into a vat C containing a suitable bath such as a sour 100 bath of sulphuric acid, or other suitable treating or bleaching liquid.

In the processes now most generally used, the material is led from the bath into a bin where it is piled by boys and is allowed to 105 remain for several hours to give sufficient time for the bath to complete its action. This method is very objectionable because of the lack of uniformity in the piling by the boys, of the soiling of the goods by dirt and 110 of the expense of the boys' wages.

In the present process, however, the fab-

ric from the bath vat C passes through squeeze rolls 16 and the piling is automatically accomplished by means of a stack or piling apparatus D, which is illustrated and described in detail in Patent No. 911,560 to Gant granted February 2nd, 1909. This apparatus comprises a vertically disposed shaft 20 communicating at the bottom with an inclined chamber or chute 21 whose delivery end is turned or curved upward and may be parallel with the feed shaft or may be inclined toward it. The material introduced into the shaft or piled therein is delivered to the receiving end of the chute 21 and as the pile in the shaft increases the accumulated material will by its own weight be carried forward and upward through the chute and at the place of delivery the end of the web or rope introduced in the stack will be at the top and may be withdrawn freely without tangling. The chute may be watertight and if desired, a solution may be caused to circulate therein. The sectional area of the stack should be governed by the weight of the fabric that is to be treated and light weight fabric may be piled in a stack of smaller sectional area than heavy fabric. If desired, several of these devices may be placed in tandem, the fabric being continually withdrawn from one machine and piled into the next to give the necessary time for chemical action.

The squeeze rolls 16 extract the excess liquor and the air contacts with the fabric as it passes into and through the stack D, completing the oxidizing or other chemical action on the fabric.

The devices are designed to handle fabric either in rope or open width or web form and operate equally as well on both.

By utilizing stacks of the type described, the time consumed for souring or otherwise treating and as later described for chemicing or further treating the fabric is greatly reduced and whereas the present pile system consumes many hours, the goods is sufficiently acted on by the sour or chemic or other treating liquor in a very short period of time.

From the piling device D, the goods is led to a washing machine E of any suitable construction and from this machine passes through wringer or squeeze rolls 22 into a vat F containing a chemic solution, such as chlorine or other suitable solution. From this fact the fabric is led through squeeze rolls 23 into a stack and piling device G exactly similar to the device D hereinbefore described. In this stack G the goods is acted on by the chemic or other treating liquor remaining in the fabric and from the stack the material is led into a washing machine H. From this machine the material passes through squeeze rolls 26 to be dried or otherwise treated, if desired.

By the process above described, all manual handling of the materials is eliminated and the fabric passes continuously through the various parts of the apparatus.

Furthermore, from the foregoing specification it will be seen that the process described eliminates entirely the ordinary sour or chemic piles and attending boys with their dirt, damages and wages and prevents any possibility of the goods remaining for an undue length of time at the bottom of the sour or chemic bin. Moreover, every portion of the material passing through the piling devices will receive the same action and be subjected in the same manner and for the same length of time to the action of the sour or chemic bath. Therefore, the goods will be uniformly treated. Any piling of the goods on trucks and transporting of the goods between the various chemical operations or the breaking of seams is eliminated thereby reducing the labor cost and making available for productive work a large amount of floor space usually occupied by the trucks. It will also be noted that the use of the keir as described makes possible continuous movement of the goods and insures a thorough and uniform cleansing thereof.

Particular attention is called to the fact that goods or material in open width or rope form can be treated in the apparatus described and the term "material" as used in the claims is intended to include material in rope or open width form.

Although one specific embodiment of the invention has been particularly shown and described, it will be understood that the invention is capable of modification and that changes in the construction and in the arrangement of the various cooperating parts may be made without departing from the spirit or scope of the invention, as expressed in the following claims.

What I claim is:

1. A method of conditioning textile material which consists in continuously progressing the material with the same end always foremost successively through a boiling vat or keir containing a cleansing solution in which the material is permeated with the cleansing liquid submerged in zigzag folds and withdrawn, passing the material through a washing machine, extracting the surplus washing fluid from the material, then saturating the material in a bath of bleaching liquor, extracting therefrom the excess liquor with which the material has been saturated, passing the material through a piling device by force derived from the weight of the material, the material in its passage through the piling device being subjected to air bleaching, again washing the material, extracting the surplus liquor therefrom and then saturating the material in a bath of

chemic or equivalent solution, extracting therefrom the excess liquor and again passing the material under force derived from the weight of the material through a piling device, where it is subjected to air bleaching, and again washing the material.

2. A method of conditioning textile material which consists in continuously progressing the material successively through a boiling vat or keir containing a cleansing solution in which the material is permeated with a cleansing liquor and withdrawn with the end first entering the keir foremost, then passing the material through a washing machine, then saturating the material in a bath of bleaching liquor, extracting the excess liquor therefrom with which the material has been saturated, and passing the material through a piling device wherein it is subjected to air bleaching, and again washing the material.

3. A method of conditioning textile material which consists in continuously progressing the material with the same end always foremost successively through a keir by continuously adding fabric to the top and simultaneously withdrawing fabric from the bottom of a vertical pile of fabric suspended in boiling caustic solution in the keir, passing the material through squeeze rolls and a washing machine and squeeze rolls, saturating the material in a sour bath of bleaching liquor, squeezing the material to extract therefrom excess liquor, passing the material by force derived from the weight thereof through a piling device, the material passing through the stack being deposited in

loose folds and being subjected to air bleaching, again washing and squeezing the material, saturating the material with a chemic solution, and extracting therefrom excess liquor, passing the material again through a piling device by force derived from the weight of the material where it is subjected to air bleaching and again washing the material.

4. A method of conditioning textile material, which consists in continuously progressing the material with the same end always foremost successively through a boiling vat or keir containing a cleansing solution, in which keir the material is permeated with the cleansing liquor and then withdrawn, extracting surplus cleansing liquor from said material and passing the material into and through a washing machine, then extracting the surplus washing fluid from the material and saturating the material in a bath of bleaching liquid, extracting from the material the excess liquor with which it has thus been saturated, passing the material through a piling device during which passage it is subjected to air bleaching, again subjecting the material to washing, extracting the surplus washing fluid therefrom and then passing the material into and through a bath of chemic or equivalent solution, extracting any excess liquor from the material and then passing the material through a piling device and then through a washing machine.

In witness whereof, I have hereunto set my hand this 22d day of May, 1923.

WILLIAM L. CONRAD.
